UNITED STATES PATENT OFFICE.

WILLIAM LOVELL, OF UTICA, OHIO.

RAIL-SUPPORT.

SPECIFICATION forming part of Letters Patent No. 769,266, dated September 6, 1904.

Application filed March 17, 1904. Serial No. 198,690. (No model.)

To all whom it may concern:

Be it known that I, WILLIAM LOVELL, a citizen of the United States, and a resident of Utica, Licking county, State of Ohio, have invented certain new and useful Improvements 5 in Rail-Supports; and my preferred manner of carrying out the invention is set forth in the following full, clear, and exact description, terminating with claims particularly specifying 10 the novelty.

This invention relates to railways, and more particularly to that class of devices thereunder known as "rail-supports."

The object is to provide effective means for 15 clamping the rail; and to this end the invention may be said to consist in certain novel structures and arrangement of parts, which will be fully described in the following specification and illustrated in the drawings, in 20 which—

Figure 1 is a perspective view of the invention as applied to a tie. Fig. 2 is a longitudinal section on line X X, Fig. 1. Fig. 3 is a plan view of one of the base members with 25 the sliding clamp in the middle and the rest of the clamping mechanism removed. Fig. 4 is a plan view of the slide. Fig. 5 is a longitudinal section through Fig. 4 on line y y. Fig. 6 is a side elevation of the outer clamp. 30 Fig. 7 is a front elevation of Fig. 6. Fig. 8 is a perspective view of the inner clamp.

The letter B designates the base member, in this case forming the end section of a tie T, which comprises, in addition to the end sections, 35 a central section C, whose length may be varied to suit different conditions. The inner ends of the base members may be provided with depending flanges F to prevent lateral creeping of the tie.

40 R indicates the rails, only one of which is shown. The base member is divided internally by a horizontal shelf 1 into two compartments, the upper of which, A, is shorter than the lower, leaving an exposed platform 2, 45 which is continuous with the shelf. The top 3 of the upper compartment is provided on its inner edge with a rectangular notch 5 and centrally with a rectangular aperture 4. A second aperture, 6, in the shelf is directly in alignment with the last-named aperture. The pur-

pose of the shelf is to facilitate removing from the open inner end of compartment A the slide which is described below.

The numeral 7 designates a sliding clamp comprising recurved ends 8, embracing lateral flanges 9 on the base member, and a straight bar 10, having on one edge a rectangular notch 11 and on the other a continuous undercut bevel 12. Notch 11 is in alignment with notch 5 and is provided at its inner edge 60 with inclined portion 13.

Occupying the upper compartment is a slide 14, having a rectangular body portion 15 and a threaded extension 16. The body portion is provided with a central aperture 17, having 65 on its side walls inwardly-projecting flanges 18. These flanges extend from the rear wall of the aperture for about half the length of the opening and are beveled upwardly and forwardly on their lower edges, forming cam- 70 ways. Thus two regions are formed in the aperture, the rearward of which is restricted by the inwardly-projecting flanges.

Apertures 4 and 6 in the base member are of such size as to receive and firmly brace the 75 stem 23 of outer clamp 19. As shown in Figs. 6 and 7, this clamp has the form of a short blunt spike. It is provided with the laterally-projecting head 20 for engagement with the rail-base and has the reduced portion 21 intermediate its length. The lower shoulders 22, formed at the junction of the reduced portion with the stem, are inclined downwardly and rearwardly, forming complementary cam- 80 ways to those on the slide. The stem on the 85 outer clamp is of such diameter as to pass readily through the forward portion of the central aperture of the slide. It is evident that a forward motion of the slide will cause the camways on the flanges to engage with 90 the camways of the clamp, forcing the latter downward.

The inner end of the upper compartment A is occupied by the rectangular body of inner clamp 23. Referring particularly to Fig. 8, 95 it will be seen that this clamp has a reduced head 24, which is adapted to fit within notch 5 in the top of the base member and is provided with an undercut bevel 25 to engage with the inclined portion of notch 11 on the 100

sliding clamp. It is further provided with a longitudinal opening 26 for the reception of extension 16 of the slide. A nut 27 fits upon the threaded end of the extension outside of 5 the clamp.

In assembling the parts of the rail-support the sliding clamp is first slipped upon the top of the base member. Then the slide is introduced into the upper compartment, so that 10 the forward portion of its aperture is in alignment with apertures 4 and 6. At this stage or earlier the rail may be placed in position. The outer clamp is dropped into place, with its head resting upon the base of the rail. The 15 inner clamp is pushed into the compartment along the projecting extension of the slide, and finally the nut is tightened. This causes the slide to move inward, and, as explained, the outer clamp is drawn forcibly down upon 20 the rail-base. Simultaneously the inner clamp is being pushed toward the rail and its head rides upon the beveled notch of the sliding clamp, jamming the latter inwardly and downwardly against its side of the rail-base.

25 While for convenience I have shown my device as applied to a tie, I wish it to be understood that the invention lies in the clamping mechanism, which I intend to claim broadly, and it is to be noted that the sliding clamp 30 may be omitted and the inner clamp forced into direct engagement with the rail without departing from the spirit of my invention.

What is claimed as new is—

1. In a device of the character described, the 35 combination with the rail and a base member having aligned vertical apertures; of a slide fitting within said member and comprising a body portion and a lateral extension, said body portion being provided with an aperture 40 adapted to align with the last-named apertures, an outer clamp comprising a head engaging with the rail-base and a stem passing through all said apertures, an inner clamp loosely mounted on the latter extension of the 45 slide and having a head for clamping the rail-base, and means for causing said slide and inner clamp to move toward each other.

2. In a device of the character described, the 50 combination with the rail and a base member having aligned vertical apertures; of a slide fitting within said member and comprising a body portion and a lateral threaded extension, said body portion being provided with an aperture adapted to align with the last-named apertures, an outer clamp comprising 55 a head engaging with the rail-base and a stem passing through all said apertures, an inner clamp mounted loosely on the threaded extension of the slide and having a head for clamping the rail-base, and a nut surrounding the threaded extension outside said clamp.

3. In a device of the character described, the 60 combination with the rail and a base member having aligned vertical apertures; of a slide fitting within said member and comprising a

body portion and a lateral extension, said body portion having an aperture adapted to align with the last-named apertures, and being further provided with inwardly-projecting flanges forming a restricted region in said 70 aperture, a clamp comprising a head adapted to clamp the rail-base and a stem passing through all said apertures and having an intermediate reduced portion adapted to receive said flanges, and means for producing a longitudinal movement of the slide. 75

4. In a device of the character described, the combination with the rail and a base member having aligned vertical apertures; of a slide fitting within said base member and having an aperture adapted to align with the last-named apertures and being further provided on its inner side walls with camways, a clamp comprising a head engaging with the rail-base and a stem passing through all said apertures 80 and having camways engaging with the camways of the slide, and means for moving said slide longitudinally, whereby the clamp is forced downward against the rail.

5. In a device of the character described, the 90 combination with the rail and a base member having aligned vertical apertures; of a slide fitting within said base member and having an aperture adapted to align with the last-named apertures, the side walls of said aperture being provided with flanges extending from the rear of the aperture to a point intermediate the length of the walls and having forwardly and upwardly inclined camways on their lower edges, a clamp comprising a head engaging 100 with the rail-base and a stem passing through all said apertures and having a reduced portion forming rearwardly and downwardly inclined camways adapted to engage with the camways on the slide, and means for producing a longitudinal movement of the slide. 105

6. In a device of the character described, the combination with the rail and a base member having aligned vertical apertures; of a slide fitting within said base member and comprising a rectangular body portion and a lateral threaded extension, said body portion having a rectangular aperture adapted to align with the last-named apertures, the side walls of 110 said aperture being provided with inwardly-projecting flanges extending from the rear of the aperture to a point intermediate the length of the walls and having forwardly and upwardly inclined camways on their lower edges, a clamp comprising a head engaging with the rail-base and a stem passing through all said apertures and having a reduced portion forming rearwardly and downwardly inclined camways adapted to engage with the camways on the slide, and a nut surrounding the end of the 115 threaded extension, whereby a longitudinal movement of the slide is produced and said camways are brought into engagement.

7. In a device of the character described, the combination with the rail and a base member 120

having alined vertical apertures; of a slide fitting within said base member and comprising a body portion and a threaded extension, said body portion having an aperture adapted to aline with the last-named apertures and being further provided on its inner side walls with camways, an outer clamp comprising a head engaging with the rail-base and a stem passing through all said apertures and having camways engaging with the camways of the slide, an inner clamp loosely mounted on the threaded extension of the slide and having a head for clamping the rail-base, and a nut surrounding the threaded extension outside the clamp.

8. In a device of the character described, the combination with the rail and a base member having a transverse compartment and alined vertical apertures; of a slide fitting within said compartment and comprising a rectangular body portion and a threaded lateral extension, said body portion having a rectangular aperture adapted to aline with the last-named apertures, the side walls of said aperture being provided with flanges extending from the rear of the aperture to a point intermediate the length of the walls and having forwardly and upwardly inclined camways on their lower edges, an outer clamp comprising a head engaging with the rail-base and a rectangular stem passing through all said apertures, and having a reduced portion forming rearwardly and downwardly inclined camways engaging with the camways on the slide, an inner clamp comprising a head adapted to clamp the rail-base and a rectangular body portion fitting within said compartment and having a transverse opening for the reception of said threaded extension, and a nut surrounding said extension outside the inner clamp.

9. In a device of the character described, the combination with the rail and base member having a transverse compartment having an open inner end, said base member being further provided with a top having flanges projecting from its sides and a rectangular notch at its inner end; of a sliding clamp on the top of said base member comprising recurved ends embracing said flanges and a straight portion having on one side a continuous undercut bevel adapted to receive the base of a rail and on the other a rectangular beveled notch alined with the notch in said top, a second clamp comprising a rectangular body portion sliding within said compartment and a rectangular head standing within the notch in the top and having an undercut bevel engaging with the beveled notch of the sliding clamp, and means for causing said clamp to move toward the rail.

10. In a device of the character described, a

hollow base member having a horizontal shelf forming an upper transverse compartment provided with an open inner end, an external platform forming a continuation of said shelf at this end, a top having flanges projecting from its sides and a notch communicating with the open end of the compartment, and alined apertures in the top and shelf; combined with a slide fitting within said compartment and having an aperture adapted to aline with the last-named apertures and being further provided with camways on its inner walls, an outer clamp comprising a head adapted to engage the base of a rail and a stem passing through all said apertures and having camways adapted to engage with the camways of the slide, an inner clamp comprising a body portion fitting within the open end of said compartment and a head standing within the notch in the top and having an undercut bevel adapted to clamp the base of a rail, and means for causing said slide and inner clamp to approach each other.

11. In a device of the character described, a hollow base member having a horizontal shelf forming an upper transverse compartment provided with an open inner end, an external platform forming a continuation of said shelf at this end, a top having flanges projecting from its sides and a notch communicating with the open end of the compartment, and alined apertures in the top and shelf; combined with a slide fitting within said compartment and having an aperture adapted to aline with the last-named apertures and being further provided with camways on its inner walls, an outer clamp comprising a head adapted to engage the base of a rail and a stem passing through all said apertures and having camways adapted to engage with the camways of the slide, a sliding clamp on the top of the base member comprising recurved ends embracing said flanges and a straight portion having on one side a continuous undercut bevel adapted to receive the base of a rail and on the other a beveled notch alined with the notch in said top, an inner clamp comprising a body portion fitting within the open end of said compartment and a head standing within the notch in the top and having an undercut bevel engaging with the beveled notch of the sliding clamp, and means for causing said slide and inner clamp to approach each other.

In testimony whereof I have hereunto subscribed my signature this the 12th day of March, A. D. 1904.

WILLIAM LOVELL.
